(57) **CLAIM**

The ornamental design for a cap for a propel/repel dispensing container, as shown and described.

DESCRIPTION

FIG. 1 is a top view of a cap for a propel/repel dispensing container of the invention;

FIG. 2 is a bottom view of the cap of the invention;

FIG. 3 is a side view of the cap of the invention, wherein the remaining side views are the same; and,

FIG. 4 is a cross-section view of the cap of the invention taken along line 4—4 of FIG. 2.
